DISHWASHER CABINET OR THE LIKE

Charles D. Dushek, Lisle, Ill., assignor to General Electric Company, a corporation of New York

Application October 29, 1956, Serial No. 43,573

Term of patent 3½ years

(Cl. D49—1)

FIG. 1

Fig. 1 is a front perspective of a dishwasher cabinet or the like showing my new design;

Fig. 2 is a front elevational view of an enlarged scale of the panel element;

Fig. 3 is a top plan view of the panel element as shown in Fig. 2; and

Fig. 4 is a sectional view taken on the line 4—4 of Fig. 2.

The dominant features of the design reside in the portion shown in full lines.

I claim:

The ornamental design for a dishwasher cabinet or the like, substantially as shown and described.
